UNITED STATES PATENT OFFICE.

GEORGE M. AGEE, OF DES MOINES, IOWA.

FEED MIXER.

Application filed October 8, 1927. Serial No. 224,969.

The present invention relates to an apparatus for mixing feed, and particularly to stock feed mixers in which a grain content is mixed with a liquid content. The liquid content which it is here contemplated shall be mixed with the grain content, is molasses.

The mixing of grain and molasses as a stock feed has long been practiced, and the commercial methods and apparatus now in use contemplate the heating of the molasses, or other sugar content, under the belief that better results are secured. The methods and apparatus which contemplate mixing heated molasses with grains are expensive to install and to operate, and, furthermore, it has been found that under some conditions, the resulting product is not entirely satisfactory, because of the danger of fermentation of the heated molasses, with consequent deleterious effect on the stock feed.

The preliminary heating of the molasses has been generally regarded as necessary to facilitate the mixing of the grain and the molasses, no efficient and commercially workable method and apparatus having been developed for handling the molasses cold or at normal atmospheric temperature.

The present apparatus is designed to efficiently handle and satisfactorily mix feed with molasses at normal atmospheric temperatures, and to give a product which is uniformly mixed, and which will be of uniform character throughout, without any balling up of the product and formation of relatively large cakes or fragments, by reason of the introduction of the molasses into the feed, an undesirable result which has been encountered in the practice of methods and the use of apparatus now known to me.

I accomplish the object aimed at by delivering the feed to a suitable receptacle, to which receptacle is also delivered, at normal temperatures, the molasses, or equivalent sweetening content, in a solid column or body, without any initial dispersion, and by subjecting the two materials within the receptacle to a violent agitation, specifically, to a centrifugal agitation, which maintains substantially the bulk of the grain content in suspension within the receptacle, and, furthermore, and which is of very considerable importance, completely breaks up and disperses the solid column of molasses immediately it enters the receptacle, and scatters it, in completely dispersed form,

throughout the body of grain, which, under violent agitation, is held substantially in suspension in said receptacle.

The process and apparatus have the advantages of being cheaper to install and operate; there is no fermentation of the molasses; the product, as it comes from the apparatus, is substantially dry, and does not have the objectionable sticky quality which is found where heated molasses is used; and since the molasses is in its normal condition, and is not thinned out by heat, a greater percentage of molasses is applied to the feed.

In order that the invention may be clear to those skilled in the art, I have shown in the accompanying drawings one physical embodiment thereof, but it will be understood that this disclosure is illustrative and in no sense restrictive, as the apparatus may be worked out in different mechanical ways, without departing from my invention.

In the drawings, which will be referred to in the following specification:

Fig. 1 is a view of the apparatus, showing generally its arrangement.

Fig. 2 is a view, at right angles to Fig. 1, of the apparatus.

Fig. 3 is a longitudinal sectional view of the mixing receptacle.

Fig. 4 is a transverse sectional view of the receptacle shown in Fig. 3, showing the inlet for the grain and the inlet for the molasses.

Fig. 5 is a transverse sectional view of the receptacle shown in Fig. 3, showing the outlet for the product after treatment.

Fig. 6 is a detail of the by-pass and its control gate.

Referring to the drawings by numbers, like numbers indicating like parts in the several views, 10 designates the mixing receptacle, which is preferably round in cross section, and may be of any suitable size in cross section and length. The receptacle 10 is closed, except for the inlet and outlet, so that material fed into it will be confined within the receptacle during treatment. The feed or grain to be treated is fed to the receptacle through the inlet 11, and, preferably, this inlet is tangentially arranged, as shown, in order to insure and maintain proper feeding of the grain to the receptacle. As here shown, the apparatus is so disposed as that the grain spout 12 from the mill or storage bin, delivers directly to the inlet, although it is obvious

that any other suitable feed to the inlet hopper may be provided.

At any suitable point in the receptacle, but, preferably, as here shown, at the bottom of the receptacle, is provided an inlet pipe 13 for the molasses, and this inlet pipe is preferably extended into the receptacle a short distance, so it projects above the bottom, and eliminates danger of feed which 10 may collect in the bottom of the receptacle in small amount, from entering the pipe and choking the flow of molasses. The pipe 13 is coupled with any suitable container for the molasses, the container here shown comprising 15 two casks 14 of the type commercially used for shipping molasses. The molasses in the container will be under pressure coming from a pressure pipe 15 connected with any suitable source of pressure, 20 which pipe 15 delivers, by suitable connections 16, to the container, and, under pressure, the molasses passes by pipe 17 to the pipe 13, leading to the receptacle 10. Suitable pressure gages for controlling pressure 25 from the pipe 15, and suitable percentage and volume controls, metering devices, and indicators are provided, but as these form no part of the present disclosure, but are independent thereof, no detailed illustration or 30 description is necessary. Under the pressure system described, the molasses will be forced through the pipe 13 to the receptacle 10, and delivered in a solid unbroken stream through the end of the pipe which 35 projects into the receptacle.

Within the receptacle 10 is mounted a shaft 18, preferably centrally disposed, and provided with suitable bearings, it having been found that under the arrangement 40 herein disclosed, a bearing 19 at the tail end of the shaft is sufficient, the head end of the shaft being coupled by suitable coupling 20 directly to the shaft of the motor M, which may be of any suitable or desired type, but, 45 preferably, is an electric motor. The shaft 18 is provided along its length within the receptacle 10 with radially disposed arms 21, the preferable arrangement being a spiral disposition of the arms about the shaft, and 50 I have found that an angular relation of 120° between the radial arms is a satisfactory one. The arms will, of course, be of different lengths, depending on the size of the receptacle, and they should be spaced 55 apart longitudinally of the shaft, approximately one-third of their lengths. It has been found that when spaced at approximately this distance, good results are secured. Too close a setting of the arms relative to one another would tend to develop a continuous spiral, and this would give insufficient agitation. Too wide a spacing of the arms from one another would also result in insufficient agitation, as wide spacing 60 would leave areas between the arms in

which agitation would be cut down to the point of inefficiency. It will be understood, of course, that other arrangements of the arms with respect to the shaft and one another, may be made, but the present plan 70 gives a satisfactory result.

The shaft 18, with its radial arms 21, is driven, as stated, from the motor M, at relatively high speed, and while the speeds may vary, I find that a speed of 1000 R. P. M. 75 is a very satisfactory speed for the usual working conditions. The revolution of the shaft 18 and its arms 20 sets up a violent agitation in the receptacle, this agitation being more particularly in the form of centrifugal agitation, tending to create a vortex centrally of the receptacle, and tending also to maintain the grain content in a constant state of agitation and suspension in the receptacle 10. The ends of the arms 21 80 should be spaced a reasonable distance from the wall of the receptacle 10, and should not be extended too close to the wall, it having been found that in an apparatus having a receptacle of approximately seventeen 90 inch diameter, there should be a clearance of approximately two inches between the ends of the arms 21 and the wall of the receptacle 10. It will be understood, of course, that in different sizes of machines, where the 95 diameter of the receptacle is more or less than the example here given, the clearance between the ends of the arms 21 and the wall of the receptacle 10 might be varied, it being desirable always, however, that there 100

be a considerable clearance for efficient results. As the arms 21 are rotated by the shaft 18, the bulk of grain is maintained in agitation and suspension, as stated, a small part of it, as the process proceeds, 105 lying against the wall of the receptacle in the rifled condition indicated by dotted lines in Fig. 3. This rifled condition, indicated by the dotted lines, becomes a fixed condition after the machine has been put 110 into operation. The feed and the molasses will build up on the wall of the receptacle between the arms, so as to produce the alternating ribs and grooves and provide the rifled form indicated, and it has been found 115 that the apparatus, after this rifled condition has been established, is highly efficient.

This formation on the inner wall of the drum, which, as stated, becomes a permanent condition as soon as the apparatus is 120 put into operation, is of very considerable value, and adds to the efficiency of the apparatus. Furthermore, by getting this deposit on the drum, and taking advantage 125 of its action on the material being treated, it is possible to utilize a relatively cheap and readily manufactured cylinder, having a smooth interior, and I avoid the necessity of providing the interior of the cylinder or receptacle with preformed corrugations in 130

the wall. It has been found, in the use of the apparatus, that after this corrugated formation is produced, and the machine has been in use for a short period, the lining becomes set, hardened, and smooth, so that it then becomes a part of the interior formation and make-up of the cylinder or receptacle.

As has been heretofore stated, the molasses 10 is delivered from the pipe 13 into the receptacle 10 in a solid unbroken column, the compression from the apparatus designed to force the molasses into the receptacle 10 being sufficient merely to deliver, in a steady 15 stream, the molasses, but without any spraying effect. The pipe 13 is of relatively large size, and, in fact, is oversize for the volume to be delivered, in order that the molasses may be fed through, even at low 20 temperatures, without the necessity of any extreme compression. The molasses, as stated, is delivered at nominal atmospheric temperature, that is, cold, and without any preliminary heating. In fact, I have found 25 that molasses kept at a temperature of substantially 60°, which can be maintained if the molasses be stored in underground tanks or vats, gives very satisfactory results, and a product is obtained which is superior. 30 As the unbroken column passes from the pipe 13 into the receptacle 10, it is at once subjected to the agitation within the receptacle, and by reason of the centrifugal action of the arms 21 and the vortex created 35 centrally of the receptacle by these rapidly revolving arms, the solid column of molasses is instantly broken up and dispersed throughout the agitating area, where it combines, while in suspension, with the suspended feed in a thorough and uniform 40 manner, it having been found that a very complete and intimate mixture results from following this method and using an apparatus designed to carry out the method. The 45 intimate mixing of the feed and molasses is facilitated by the frictional heat generated by the passage of the mixture over the corrugated surface referred to. This, it will be noted, maintains both the feed and molasses at a uniform temperature.

The method is a continuous one, in that the feed and the molasses are being continuously introduced into the receptacle 10, and the finished product is continuously 50 passing out from the outlet 22 at the tail end of the receptacle 10. The outlet 22 is preferably tangentially disposed in a manner similar to that of the inlet 11, it having been found that under the high speeds at 55 which the machine is operated, a tangential feed and a tangential delivery is preferable to radial inlet and outlet openings, for the reason that, with a radially disposed inlet and outlet there is a tendency at the inlet 60 end to force the feed back, rather than to

draw it into the receptacle, and at the outlet end there is a tendency to sweep the finished product past a radial outlet, whereas with the tangential inlet and outlet, the feed will be readily drawn in and readily leave 70 the receptacle.

The product delivered from the receptacle will pass through a suitable down spout 23, and, by means of any suitable delivery chute 24, here shown as a flexible, hollow conveyor, 75 be delivered to any suitable point of delivery, as, for example, the truck 25.

It has been pointed out that the feed or grain may come through the grain spout 12 directly from the mill or any suitable storage bin. When the apparatus is coupled up to the grain spout in this fashion, particularly in custom mills, it may be desirable to provide means by which grain may be delivered without passing it through the apparatus described. In other words, a customer might not wish to have a certain batch of grain or feed subjected to the molasses treatment, or might wish to have a portion only of a batch treated. In order 90 that this condition may be met, I have provided a construction whereby feed may be by-passed from the mill or storage bin around the apparatus and delivered directly to the delivery end and passed to the conveyor spout 24, to be delivered to the truck 25 or any other suitable receptacle or point of delivery, it being understood that under these conditions of by-passing the material, the motor and the mixing apparatus would 95 be at rest.

In Figs. 4, 5 and 6, I have illustrated this by-pass arrangement in detail. As shown in Fig. 4, the inlet 11 is provided with a gate 26 which can be turned to the full line 105 position shown, or the dotted line position shown. In the full line position of the gate, the feed will pass to the receptacle 10 for treatment, but if it is not desired to subject the feed to treatment, the gate 26 will be 110 turned to dotted line position and the feed will then enter the by-pass 27, which is inclined, as shown, and be delivered directly to the outlet 22 and flow down the spout conveyor 24.

This gives a very simple and efficient control of the material, and one which enables it to be directed either to the molasses applying instrumentalities, or to be carried around the mixing receptacle and delivered 115 in its original milled condition.

Any desired means for controlling the gate 26 may be provided, but I have here shown the gate 26 as mounted on a shaft suitably journalled in the walls of the inlet, and the end of this shaft is provided with a lever arm 28 to which is attached draft ropes or chains 29 depending, as shown, on opposite sides, so that by pulling on one or the other of the draft devices 29, the gate 120 125 130

26 may be thrown to its different positions. In the particular arrangement here shown, one of the draft devices passes over a small pulley or sheave 30, and is attached to the 5 lever or crank arm 28, while the other draft device is attached directly to the arm.

In the operation of the apparatus, it has been found that the material under treatment gradually works from the inlet end 10 toward the outlet end, this being due to the spiral disposition of the arms about the shaft, which tends to create a movement toward the delivery end of the receptacle, where, as will be obvious, there is less resistance 15 than at the inlet end, for the inflowing grain or feed at the inlet end of the receptacle 10 offers more resistance to the flow than the relatively unobstructed outlet end. Furthermore, the air current will flow from 20 inlet to outlet and agitate and help to carry the material toward the outlet end.

By the practice described and the apparatus designed to carry it out, I am able to produce, with any form of grains, either 25 whole grain or grain which has been milled, and cold molasses, a very superior and uniformly mixed sugar feed, and one which has the light, dry, flocculent condition which is highly desirable. Furthermore, the sugar 30 or molasses content is increased, and danger of fermentation of the final product, which sometimes results where the molasses is heated, is entirely eliminated.

It will be understood that while I have 35 disclosed a particular method and apparatus for carrying out that method, that such variations in method and such changes in apparatus as do not depart from the scope of the invention as stated in the appended 40 claims, may be made, and still be within the range of my invention. It will be understood, further, that while the method and apparatus is shown as a feed mixer, it may be adapted to and used with other combinations of granular and liquid materials 45 which it is desirable to mix in a complete and satisfactory way.

No claim is herein made to the novel features of the method described in the foregoing specification as the same forms the subject matter of a divisional application Serial No. 287,534.

I claim:

1. In apparatus of the class described, the 55 combination of a closed receptacle having a tangential inlet for feed and a tangential outlet for the completed product, a pipe to deliver an unbroken stream of the liquid content to said receptacle, means for delivering 60 the liquid content under pressure to said pipe, and a rotary shaft having a plurality of radial arms spirally disposed on said shaft within the receptacle to agitate the 65 feed and disperse and commingle with the

feed the liquid content delivered by said pipe.

2. A mixing drum having alternate circumferential ribs and grooves of granular material deposited on its inner surface. 70

3. A mixing drum having alternate circumferential ribs and grooves of adherent granular material deposited on its inner surface.

4. A mixing drum having alternate circumferential ribs and grooves of granular material mixed with a binder deposited on its inner surface. 75

5. In an apparatus of the class described, the combination of a mixing receptacle having an inlet at one end and an outlet at the other end, a by-pass leading from the inlet to the outlet, a gate in said inlet, and means for moving said gate to direct material passing through the inlet to the receptacle 85 or to the by-pass. 80

6. In an apparatus of the class described, the combination of a mixing receptacle having an inlet at one end and an outlet at the other end, a by-pass connected with said inlet and delivering to the inlet and delivering to the outlet, a gate centrally disposed in said inlet, and means for moving said gate to deliver material to the mixing receptacle or to the by-pass. 90

7. In an apparatus of the class described, the combination of a mixing receptacle, an inlet spout delivering to said receptacle over a portion of its area, a by-pass to which a portion of the inlet spout delivers, an outlet spout at the delivery end of said mixing receptacle to which said by-pass delivers, and a gate in the inlet spout adapted to be set to deliver material to said mixing receptacle or to said by-pass. 95

8. In an apparatus for the purpose described, the combination of a closed receptacle having an inlet for grain and an outlet for the completed product, means for delivering molasses at normal temperature to the 100 receptacle, stirring means in the receptacle for commingling particles of grain and molasses and moving the mixture toward the outlet, and supplemental means in the receptacle for retarding movement of the mixture 105 toward the outlet and in cooperation with the stirring means imparting frictional heat to the mixture. 110

9. In an apparatus for the purpose described, the combination of a closed receptacle having an inlet for grain and an outlet for the completed product, means for delivering molasses at normal temperature to the 115 receptacle, and stirring means in the receptacle adapted to initially cause commingled particles of grain and molasses to form a transversely curved, longitudinally corrugated, surface extending to the outlet and to 120 subsequently effect movement of the com- 125

130

mingled particles over said surface to the outlet, substantially as and for the purpose described.

10. In an apparatus for the purpose described, the combination of a closed receptacle having an inlet for grain and an outlet for the completed product, means for delivering molasses at normal temperature to the receptacle through an opening in the bottom, 10 and a rotary shaft provided with stirring arms adapted, as the shaft rotates, to commingle particles of grain and molasses to initially form a corrugated surface extending to the outlet of the receptacle and to subsequently effect movement of commingled particles over said surface to the outlet, the friction between the mixture and said surface induced by the stirring arms raising the temperature of the grain and molasses uniformly.

11. An apparatus for preparing sweetened feed for live stock, comprising a receptacle provided with a feed inlet and an outlet for the completed product, located adjacent opposite ends of the receptacle, respectively, means for introducing into the receptacle near the end thereof adjacent the feed inlet sweetened liquid under pressure, and means in the receptacle to agitate the feed therein and commingle said liquid therewith.

12. An apparatus for preparing feed for live stock, comprising a receptacle provided at one end with a feed inlet and in its bottom adjacent the same end with an inlet for liquid, an outlet for the completed product being provided at the other end of the receptacle, and means in the receptacle to agitate the feed therein and commingle it with the liquid

uid while feeding the mixtures to the outlet.

13. An apparatus for preparing feed for live stock, comprising a closed receptacle having its side walls provided near its ends, respectively, with a feed inlet and an outlet for the finished product, means for delivering liquid under pressure through an opening in the bottom of the receptacle near the end thereof adjacent the feed inlet, and means in the receptacle to agitate the feed therein and commingle it with the liquid while feeding the mixture to the outlet.

14. An apparatus for preparing feed for live stock, comprising a closed receptacle having at one end a feed inlet and at its opposite end an outlet for the finished product, a pipe for supplying liquid through the bottom of the receptacle adjacent the inlet end thereof, said pipe projecting into the receptacle above the inner face of the bottom, and means in the receptacle to agitate the feed therein and commingle it with the liquid while feeding the mixture to the outlet.

15. An apparatus for preparing feed for live stock comprising a closed receptacle provided adjacent one end with feed and liquid inlets, whereby liquid is introduced into the receptacle in a direction substantially opposite that in which feed is introduced, the receptacle having an outlet for the finished product adjacent its opposite end, and means in the receptacle to agitate the feed therein and commingle it with the liquid while feeding the mixture to the outlet.

In testimony whereof I have hereunto set my hand.

GEORGE M. AGEE.
